UNITED STATES PATENT OFFICE.

RODNEY S. VAN FLEET, OF FINDLAY, OHIO.

CORNER JOINT FOR SCREEN AND OTHER FRAMES.

Application filed July 20, 1921. Serial No. 486,241.

To all whom it may concern:

Be it known that I, RODNEY S. VAN FLEET, a citizen of the United States, residing at Findlay, in the county of Hancock and State of Ohio, have invented a new and useful Improvement in Corner Joints for Screen and Other Frames, of which the following is a specification.

This invention has reference to corner joints for screen and other frames, and follows in general the lines of the corner joint construction shown and described in Letters Patent No. 1,161,169 for a corner joint for screen and other frames, patented November 23, 1915, to F. W. Van Fleet and myself.

The object of the invention is to produce a simple, practical and inexpensive corner joint, designed particularly for screen frames similar in appearance to a mortise and tenon or miter joint, but providing for adjustability to adapt the frame to windows of different sizes, and wherein the screen material may be firmly and smoothly attached, with the whole structure free from liability of loosening or pulling apart.

In accordance with the invention, the joint is formed by the junction at each corner of the frame of two bars, with one carrying a plate with a hook projection beyond which the plate extends, while the other bar is provided with a rabbet and a kerf adapted to receive the hook and plate extension, whereby the two bars at the joint may slide together lengthwise of one bar to provide for the adjustment of the size of the frame and for the reception of brads or other fastening devices to ultimately unite the two bars against possibility of displacement, so that the frame when completed will provide a particularly rigid structure to receive and hold the screen material in a taut condition, whereby the finished screen, besides fitting the window opening, will present and maintain a neat appearance without sagging or buckling of the screen material.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from

the salient features of the invention as expressed in the appended claims.

In the drawings:

Fig. 1 is a perspective view of one corner 60 of a window screen with the parts assembled and carrying the screen material.

Fig. 2 is a perspective view, with parts in section, of one of the bars of the frame.

Fig. 3 is a perspective view of one end of 65 another bar of the frame meeting the first named bar.

Fig. 4 is a section lengthwise of the joint showing the meeting ends of two bars secured together.

Fig. 5 is a section on the line 5—5 of Fig. 4.

Fig. 6 is a perspective view of one of the corner anchor plates.

Referring to the drawings, there are 75 shown two bars or frame members 1, 2 respectively, the drawing showing the corner meeting ends of the two bars, which when properly joined constitute a corner joint. Along one long edge of each bar or rail, 80 there is produced a rabbet groove 3, of appropriate width and depth to receive a strip 4 of molding and screen material 5, which may be of the usual woven wire screening. At the inner edge of each rabbet 3 there is 85 also produced a longitudinal groove 6. The bar 1 has a kerf 7 and the bar 2 has a kerf 8 entering the bar flush with the face of the groove 6.

Fast to the bar 2 is a plate or hook 9 provided with an extension 10 at one end and a similar extension 11 at the other end and bent intermediately between the extensions into a channel 12 forming a bill or hook with the two extensions 10 and 11 in alignment. The extension 11 enters the kerf 7 in the bar 1 and the extension 10 enters the kerf 8 in the bar 2. The plate or hook 9 is made fast to the rail 2 by nails or brads 13 driven through the rail 2 thereby piercing 100 the plate extension 10, while the extension 11 is seated and slid able in the kerf 7 and when the parts are brought into proper relation, other brads or nails 14 driven through the bar 1 and the extension 11 complete the 105 joint. The bar 1 is provided on the face remote from the rabbet 3 in which the molding 4 is seated, with a bevel 15, in which a tongue 16 along the corresponding edge of the bar 2 seats. Between the bevel 15 and 110 the rabbet 3 on the other side of the bar 1, there is formed a tongue 17 adapted to seat

in a groove 18 produced across the end of the rail 2 by the tongue 16 and another tongue 19 on the opposite side of the rail 2. The groove 6 which is formed in and extends 5 along one face of the tongue 17 coincident with the rabbet 3 in the bar 1 has the hook 12 of the plate 9 seated therein with the extension 10 in the kerf 8 and, when the parts are assembled, with the extension 11 in the 10 kerf 7 of the bar 1. The hook or bill 12, on account of its channel form, provides a stiff member resistant to side movements and when the plate 9 is lodged between the 15 two rail members at the joint, the rigidity of the hook member or plate is sufficiently pronounced to permit the employment of relatively thin gage metal, with the plate 9 materially stiffened and made resistant to bending strains by the channel 12, where- 20 fore when the parts are assembled and the nails 13 and 14 are driven through the plate 9 into the respective rails, the joint is markedly resistant to distortion in any direction.

By making the kerfs, particularly the 25 kerf 7, of sufficient length, the rail 2 may be driven inwardly for a considerable distance lengthwise of the rail 1 and the outwardly projecting portion of the latter subsequently cut off, thereby providing for the production 30 of frames of several different standard sizes.

By making each bar with one end capable 35 of receiving the opposite end of the other bar, the bars may be interlocked in the reverse manner at the opposite ends, whereby 40 one bar may have the bar meeting it at the corner or joint driven thereon in the direction of the length of the channel 12 and then the second bar at the other end may have a bar driven thereon at the joints in 45 the direction of the length of the second bar, so that the frame as a whole, may be made smaller or larger as the case may be, by having the bars driven together in progressive order about the frame. The length of the

50 kerfs 7 and 8 agree with the amount of adjustment provided, whereby the frames may all be of the same size as manufactured and sold and may then be assembled and projecting ends of the bars cut off before the screen netting 5 is applied and the molding 4 is nailed on to complete the frame.

The hook or bill 12 in the metal corner 55 plate entering the groove 6 serves to draw the two parts of the joint firmly together and any loosening of the joint may be avoided by driving a corrugated anchor nail 20 or fastener across the meeting edges of the rails at the joint.

The use of the metal plate 9 with exten- 60 sions thereof on opposite sides of the channel 12 contributes materially to the production of an exceptionally strong joint by the use of very thin metal and very little strength of the wood is sacrificed, because 65 of the extremely small amount of wood

which must be cut away. The plate 9 which extends on either side of the channel 12 is adapted to enter both bars or rails for a considerable distance beyond where the channel is embedded in the bars, so that the extensions of the plate have a particularly strong hold in the kerfs provided for them. 70

The slot or groove in the rails or bars to receive the metal channel or hook part 75 contacts to interlock both the wooden and metal portions to make a knock-down draw-joint frame handy, strong, easily adjusted to the fraction of an inch, neat and regular in appearance, as well as economical to manufacture and answering all the requirements of 80 the trade.

The metal plate or hook structure is so 85 embedded in the two rails or bars that there is no chance of pulling the channel or hook open under strains to which it may be subjected and the joint is always tight and is stronger than joints for the same purpose, 90 as heretofore proposed. The joint may be manufactured at less cost than other similar joints, because of less weight of metal 95 and the fact that the relatively thin sheet metal may be easily cut and stamped and may be permanently anchored in one of the bars by brads which may be driven into the wood through the metal, thus avoiding drilling holes, so that in the items of both hardware and labor, there is a marked saving effected. 95

The appearance of the joint is improved, 100 because of the absence of screws or large metal nails or pins on the surface of the frame, and the hiding of the metal plate, which is wholly embedded in the frame, and the ample space provided for the fastening of the screen cloth, or netting. 105

The invention also has the advantage of 110 ready assemblage being more quickly put together than occurs with other forms of corner joints.

What is claimed is:—

1. A corner joint for window screen and other frames, comprising two bars meeting at right angles, one bar carrying a metal plate with a transverse hook or channel beyond opposite sides of which the plate extends, one of the bars having a rabbet extending lengthwise thereof, and a groove substantially flush with the rabbet, both bars having kerfs therein receiving the extensions of the plate with the channel portion of the plate located in the groove to move therewith, the joint being completed by means of small nails, and the joint plate being hidden from view and traversed by the nails. 115

2. A corner joint for window screen and other frames, comprising two abutting bars, in angular relation, one bar having a mortise groove across one end with tongues on opposite sides defining the groove, one of 120 125 130

- the tongues being beveled on one side and the other bar having a beveled portion receiving said beveled tongue and having a lengthwise rabbet receiving the other tongue 5 of the first-named bar, and also having a lengthwise groove in the rabbet, both bars having alined kerfs flush with the groove in the second bar, and a flat plate with an intermediately located hook or bill offset from 10 one face of the plate and slidably seated in the groove, with opposite ends of the plate located in the kerfs in the two bars, the joint being made rigid by securing the plate to both of said bars.
- 15 3. A corner joint for window screen and other frames, comprising two bars abutting at right angles, with one bar having a groove extending lengthwise thereof and the respective bars having kerfs lying in one 20 plane when the joint is assembled, and a plate having an intermediately located channel or bill offset from one face of the plate and disposed in the groove, with the plate having alined extensions located in the kerfs 25 in both bars.
4. In a corner joint for frames, a pair of frame members, the end of one member engaging one longitudinal edge of the other in interlocking relation, each of said members 30 having a rabbeted portion, one of said members having a groove at the joint end in the rabbeted portion, and an anchor plate embedded in and secured to both of said members, the inner face of said anchor plate 35 being flush with the rabbeted portions and said plate having a channel portion engaging said groove to prevent racking of said frame.
5. In a frame construction, comprising 40 frame members, rectangular in section, one of said frame members having a tongue across the width of the end on one side and
- a longitudinal kerf adjacent said tongue, the adjacent frame member having a rabbeted portion along one of its longitudinal 45 edges receiving the tongue of the first-named member and having a groove at the bottom of the rabbeted portion, and having a lateral kerf cut flush with said rabbet, and anchoring means secured in said kerfs, said anchoring means having a projection in said groove adapted to strengthen the joint.
6. In a corner joint for frames, a pair of frame members, the end of one member abutting the side of the other, said end having a transverse channel, the side of the adjacent member having a tongue to fit in said channeled end, kerfs cut in both of said members in the same plane as two of the contiguous sides of said tongue and channel, 50 a groove in one of said contiguous sides, and an anchor plate secured in said kerfs, said anchor plate having a transverse channel interlocking with said groove to strengthen said joint.
7. In a corner joint for frames, two frame members having their ends rabbeted and disposed in overlapping relation, an anchor plate comprising a relatively thin oblong plate having a transverse channel intermediate its ends extending entirely across the same, said plate being inserted between the overlapping parts of the frame members in concealed relation and said frame members having kerfs in which the ends of the 70 plate are secured, and one frame member having a channel member across its rabbeted end to receive the channel portion of the plate.
- In testimony, that I claim the foregoing 75 as my own, I have hereto affixed my signature.

RODNEY S. VAN FLEET.
